DESIGN FOR A COMBINED WRINGER AND CASING FOR DOMESTIC WASHING MA- CHINES

Walter D. Teague, Forest Hills, N. Y., assignor
to Nineteen Hundred Corporation, Bingham-
ton, N. Y., a corporation of New York

Application September 18, 1934, Serial No. 53,318

Term of patent 14 years

To all whom it may concern:

Be it known that I, Walter D. Teague, a citizen of the United States, residing at Forest Hills, in the county of Queens and State of New York, have invented a new, original, and ornamental Design for a Combined Wringer and Casing for Domestic Washing Machines, of which the following is a specification, reference being had to the accompanying drawing, forming a part hereof, in which:

The drawing is a perspective view of a combined wringer and casing for domestic washing machines.

As viewed from the opposite side the construction will appear the same except that the relation of the wringer to the casing will be reversed and the various control handles on the wringer and casing extending in the direction from which the view is taken and the drain pipe shown near the bottom of the casing will not be seen.

I claim:

The ornamental design for a combined wringer and casing for domestic washing machines, as shown and described.

WALTER D. TEAGUE.
